UNITED STATES PATENT OFFICE.

JOSEPH M. CRUCET, OF NEW YORK, N. Y.

LAMP SHADE.

1,421,415.

Specification of Letters Patent.

Patented July 4, 1922.

Application filed November 19, 1921. Serial No. 516,316.

To all whom it may concern:

Be it known that I, JOSEPH M. CRUCET, a citizen of the United States, and a resident of the city, county, and State of New York, 5 have invented certain new and useful Improvements in a Lamp Shade, of which the following is a full, clear, and exact description.

Among the principal objects which the 10 present invention has in view are: to form a solid and durable frame for shades of the character mentioned; to adapt the frame to be readily upholstered; to ventilate the frame; to avoid burning the same; and to 15 simplify and cheapen the construction.

Drawings.

Figure 1 is a top plan view of a lamp shade constructed and arranged in accordance with the present invention.

Figure 2 is a side view of the same partly in section, the section being taken on the line 2—2 in Fig. 1.

Figure 3 is a detailed view in section, 25 showing the construction of a ground ring with which the shade is provided, and means for connecting the panel members of the shade therewith, the section being taken as on the line 3—3 in Fig. 1.

Figure 4 is a detailed view on enlarged scale showing the cross section of the annular member of the shade frame, the section being taken as on the line 4—4 in Fig. 1.

Figure 5 is a detailed view in section, the 35 section being taken as on the line 5—5 in Fig. 1.

Figure 6 is a detailed view on enlarged scale showing fragments of translucent panels with which the shade is provided, 40 and means employed for supporting the same in service.

Description.

Heretofore, lamp shades have been constructed of a variety of materials both for the frame and for the translucent covering panels or ornamentation. The frames, however, have usually consisted of wire or of ratan or similar materials. Wood has been 45 used very slightly if at all, due to the difficulty and expense incident to forming the necessary joints.

As seen in the drawings the frame when constructed in accordance with the present 55 invention has a rim 11. The rim may be circular or poly lateral. The rim as seen best

in Fig. 4 of the drawings has adjacent the lower edge thereof a rabbeted member 12 within which rests the head 13 of a fringe 14. The rim is provided above the member 60 12 with a recess 15 disposed lengthwise in which may be mounted adhesively or otherwise an ornamental fillet to enrich the appearance of the frame.

The rim is operatively connected with the 65 ground ring 16 by a number of radially disposed ribs 17. The ribs 17 as seen best in Fig. 5 of the drawings are rabbeted on both side edges to form a T-shape in cross section, the web 18 whereof supports the exposed flanges 19 which overhang the translucent panels 20.

The ground ring 16 is circular in form having a molded surface 21 and a pendent flange 22. The ring 16 has an open center 75 divided horizontally in service by a metal disk 23. The disk 23 is held permanently in the ring 16 by a wooden thimble 24 which as seen best in Fig. 3 of the drawings has a vertical extension and horizontal flange 25. 80 The flange 25 of the thimble 24 is usually as wide as the lower edge of the flange 22 of the ring 16 being used in practice to cover the lower edge or face of the said flange 22, and to support the ends of the ribs 17. To 85 receive the ends of the ribs 17 the flange 22 of the ring 16 are cut away to form recesses to receive the ends of the ribs 17 and of the web 18 thereof, the top of said ribs forming the flanges 19 being cut back to 90 avoid the molded surface 21 of the ring 16.

When the ends of the ribs 17 are thus disposed in the recesses formed in the flange 22 they are housed therein by placing the thimble 24 in position which is then permanently secured adhesively or otherwise to the flange 22. When the thimble 24 is thus disposed, the recesses in the ring 22 are covered at the inner side of the flange 22 and at the underside thereof. It is obvious that 100 the ribs 17 are thus held positively in position, and that the structure formed thereby is clean, workmanlike and strong.

When the ribs 17 have been mounted, it will be found that the frame provides a 105 series of flared openings in which is mounted the panels 20. The panels 20 are usually constructed of mica or parchment or similar material. In some instances finer material such as transparent silks are employed. The panels are held in service by fillets 26. The fillets 26 are secured to the 110

ribs 17 as shown best in Fig. 5 of the drawings.

The disk 23 has a central perforation 27. The perforation 27 is provided to receive a central rod usually screw-threaded, of the lamp pedestal. When the rod is secured firmly in these perforations it is obvious that the frame is held rigidly in service position. A series of perforations 28 surrounding the central perforation 27 is usually employed for ventilating the lamp shade permitting the heated air to rise upward therefrom.

When the wood-work above described has been united in the manner explained it may be coated or covered with any suitable form of service ornamentation such as molded plaster or mastic compositions, common to the manufacture of picture frames and articles of a similar character. When so ornamented and provided with the fringe 14, a handsome and substantial structure is obtained.

Claims:

- 25 1. A lamp shade comprising a continuous outer rim; a center ring, said ring having a series of bottom opening recesses; a plurality of radial ribs structurally connected 30 with said rim, the inner ends of said ribs being disposed in the recesses in said ring; and a housing member permanently attached to said ring to cover the inner and lower surfaces thereof.
- 35 2. A lamp shade comprising a continuous outer rim; a center ring, said ring having a series of bottom opening recesses; a plu-

rality of radial ribs structurally connected with said rim, the inner ends of said ribs being disposed in the recesses in said ring; 40 a housing member permanently attached to said ring to cover the inner and lower surfaces thereof; and a supporting member extending across the opening in said ring to receive the support for said shade. 45

3. A lamp shade comprising a continuous outer rim; a center ring, said ring having a series of bottom opening recesses; a plu- 50 rality of radial ribs structurally connected with said rim, the inner ends of said ribs being disposed in the recesses in said ring; a housing member permanently attached to said ring to cover the inner and lower surfaces thereof; and a metallic disk shaped to conform with the central opening of said ring, and for being held in service relation thereto by said housing member. 55

4. A lamp shade comprising a rim constructed of wood having a rabbeted recess adjacent the lower exposed edge thereof; 60 an open centered ring concentric to said rim; a plurality of radially disposed ribs structurally connected with said rim and said ring, said ribs being rabbeted at the sides to form receptacles for translucent 65 panels; a supporting member for the inner ends of said ribs, said member being permanently and structurally connected with said ring; and a metal disk mounted in said ring extending across the passage therein 70 and provided with openings for ventilating said lamp shade.

JOSEPH M. CRUCET.
